UNITED STATES PATENT OFFICE

167,483

CHINA RACK

Graziano Russo, Detroit, Mich.

Application March 1, 1951, Serial No. 14,342

Term of patent 14 years

(Cl. D80—10)

To all whom it may concern:

Be it known that I, Graziano Russo, a citizen of the United States of America and a resident of the city of Detroit, county of Wayne, State of Michigan, have invented a new, original, and ornamental Design for a China Rack, of which the following is a specification, reference being had to the accompanying drawing, forming a part hereof:

Fig. 1 is a perspective view of a china rack, showing my new design;

Fig. 2 is a top plan view of said rack.

I claim:

The ornamental design for a china rack, as shown.

GRAZIANO RUSSO.
